Primary Examiner—James Gandy*Assistant Examiner*—Linda Brooks*Attorney, Agent, or Firm*—Amster, Rothstein & Ebenstein[57] **CLAIM**

The ornamental design for a display stand, as shown and described.

DESCRIPTION

FIG. 1 is a perspective view from the front, top, and one side of a display stand showing my new design, with the movable shelves in a position of use, with the bottles and logo shown in broken lines for purposes of illustration only and forming no part of the claimed design;

FIG. 2 is a perspective view thereof from the front, top, and the other side, with the movable shelves in a position of non-use;

FIG. 3 is a rear elevational view of FIG. 2;

FIG. 4 is a top plan view of FIG. 1;

FIG. 5 is a bottom plan view of FIG. 1; and,

FIG. 6 is the same as the perspective view shown in FIG. 1, with two of the movable shelves in a position of use.
